UNITED STATES PATENT OFFICE

MAX MEYERSON, OF NEW YORK, N. Y.

CONTAINER

Application filed May 19, 1927. Serial No. 192,747.

This invention relates to a container, being in the nature of an improvement upon the structure shown and described in my pending application Serial Number 175,986, filed

5 March 17th, 1927.

An object of the present improvement is to provide a more compact and efficient form of joint and re-inforcing element by which to connect together the several parts or wall

10 pieces of the container.

A more detailed object is to provide an improved connecting and re-inforcing element by the use of which a container may be formed principally of sheet fibre-board, ordinary cardboard, or other appropriate light and strong material, and in which no prominent projections will be present at the joints either interiorly or exteriorly of the container.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claim.

In the accompanying drawings which are to be taken as a part of this specification, and in which I have shown merely a preferred form of embodiment of the invention:

Fig. 1 is a side elevational view partly in vertical section of a container constructed in accordance with this invention.

Fig. 2 is an enlarged fragmentary detail sectional view taken substantially upon the plane of line 2—2 of Fig. 1.

Figs. 3 and 4 are similarly enlarged fragmentary detail sectional views illustrating modified forms of joint structure.

Referring to the drawing for a detailed description of the structure illustrated therein, the container will be referred to generally as comprising a side wall or walls L, and a bottom wall G. It may be constructed of any desired shape or size, but for convenience of illustration is here shown as being cylindrical.

The side walls L are made up of a series of

separate pieces or sheets as 3—3. These may be of thin sheet fibre-board, cardboard, or other suitable material. They are each of a height to extend preferably from the top to the bottom of the container and may be of any desired width so that any number thereof according to their width, and the size of the container, may complete the entire side wall structure, it being borne in mind of course that the greater the number of these pieces

55 for a given size of container the greater will be the number of joints present for connecting said pieces together vertically of the container.

60 The side wall pieces have their adjacent vertical edge portions as 4—4 disposed in alignment with each other but slightly spaced apart and all are held together by top and bottom binder strips 5 and 6 respectively.

65 To connect the edge portions 4—4, and thus unite the side wall pieces, suitable joint forming and re-inforcing strips H are provided one for each joint. These joint-strips are each preferably formed of a strip of sheet metal the central longitudinal portion of

70 which is preferably corrugated or otherwise shaped as at 7 to increase its vertical strength. At opposite sides of this corrugated portion the material of the strip as at 8—8 is bent over upon itself to a mid-point as at 9 where

75 it is again bent outwardly upon itself as at 10—10. The finished strip thus comprises three distinct layers of material, the outer or corrugated layer 7, an intermediate layer comprising the parts 8—8, and an inner layer

80 comprising the parts 10—10. The parts 7 and 8 are intended to have permanent relation to each other at all times but the parts

85 10—10 constitute what may be termed fastening legs since they are relatively movable and are intended to be bent into tight engagement with the wall pieces 3—3 after said wall pieces have been engaged relatively into the pockets as 11—11 provided to receive them

90 between the portions 8—8 and the fastening legs. The normal position of the fastening legs is clearly indicated by the dotted lines in Fig. 2, and after the side wall pieces 3—3 have been moved into the pockets said legs are

95 bent firmly against the inner surface of the

100

said wall pieces, that is to the position shown in full lines in Fig. 2, the point of bend of said legs being in the portions as 12—12 where they connect with the portions 8—8, said portions 12—12 being accommodated within the small opening which, as above mentioned, is provided between the adjacent edges of the wall pieces 3—3.

At their outer or free edges each of the 10 fastening legs is provided with tangs as 13 thereon arranged to sink into the material of the wall pieces 3—3, said tangs being preferably made sufficiently long so that in the completed joint they will extend entirely 15 through the wall pieces and bend over or mushroom against the inner surfaces of the portions 8—8 and thus become riveted permanently to said wall pieces.

The two outer layers of each joint-strip, as 20 the layers 7 and 8—8, extend throughout the length of the strip, that is from the extreme bottom edge to the top edge of the wall pieces, 3—3, and are caught beneath the binder strips 5 and 6, said binder strips being of U-cross section, as clearly illustrated at the right in Fig. 1. The fastening legs 10—10 may also extend throughout the length of the other portions of the joint-strip if desired but they 30 preferably are cut-off at their opposite ends as at 14—14 for the sake of compactness and neatness in the localities where the joint-strips are received within the binder strips 5 and 6.

It will be apparent that joints formed by joint-strips as herein shown and described 35 will be strong and durable without the use of separately formed rivets at any point. The interior of the container will be entirely devoid of rivet heads or other objectionable projections which might interfere with the 40 use of the container for such purposes as the storing and handling of silks, fine fabrics, and the like. And at the same time the joint-strip will constitute a reinforcing element extending throughout the height of the container and affording great strength in all 45 directions.

Obviously the bottom wall G of the container, or a top wall if such should be desired, might readily be made up of individual pieces connected together by the use 50 of joint-strips in the same manner as already described for the side walls, and in this connection it will be pointed out that the binder strip 6 at the bottom of the container is provided with a flange portion 15 between which and the bottom wall piece the opposite ends of the joint-strips may extend in the same manner as explained for the opposite ends of the joint-strips with respect to the side flanges of the binder strips 5 and 6, and also as more fully referred to in the co-pending application cited.

The joint-strips will preferably have their 65 corrugations 7 discontinued at the ends

of the strips where they engage the binder strips.

In the modification Fig. 3 the structure is the same as already described except that in this instance it is proposed that the joint-strip shall be of general S-shape in cross section providing oppositely facing pockets as 16 and 17 therein for receiving the vertical edge portions of the wall pieces 3—3, said edge portions being in this instance in overlapping relation. The outer and inner legs as 18 and 19 of the S are intended to be bendable at the points 20 and 21 respectively for receiving and clamping the wall pieces, and they are provided with edge tangs as 22—22, all in substantially the same manner and for the same purpose as already described.

In the modification Fig. 4 it is proposed that the joint-strip shall consist of two separate members as 23 and 24, each being of U-shape and each being arranged to straddle one edge of the adjacent wall pieces 3—3, the legs of the U in each instance being intended to be bent to receive and clamp the interposed wall pieces 3—3, and having edge tangs as 25 and 26, all in substantially the same manner and for the same purpose as already described.

In this instance the adjacent edges of the wall pieces are arranged in alignment substantially the same as in the structure Figs. 1 and 2, and it is proposed that the abutting portions of the two members of the joint-strip may be connected together in any suitable manner as by means of electric welding, soldering, or other appropriate medium as indicated at 27.

The outer portions of the joint-strips in Figs. 3 and 4 may be formed with corrugations for added strength if desired.

As many changes could be made in this construction without departing from the scope of the invention as defined in the following claim, it is intended that all matter contained in the above description or shown in the accompanying drawings, shall be interpreted as illustrative only and not in a limiting sense.

Having thus described my invention, what I claim as new and desire to secure by Letters Patent is:—

A container comprising wall parts formed of sheet material, said wall parts having juxtaposed edge portions spaced apart, and a joint strip extending longitudinally of said juxtaposed edge portions, said joint-strip having one part arranged to overlie outer surface portions of said wall parts at opposite sides of the opening between said wall parts, said joint-strip having other parts arranged to extend through the opening between said wall parts being bendable and thereby adapted to be bent into clamping engagement against the inner surface of

said mentioned portions of the wall parts,
said last mentioned parts of the joint-strip
having pointed tangs provided at the edge
thereof turned abruptly toward the inner
surface of the mentioned portions of the
wall parts adapted thereby to be impaled
5 into said mentioned portions of the wall
parts when said last mentioned parts of the
joint-strip are bent into clamping engage-
ment, and the mentioned outer part of the
joint-strip being relatively wider than the
10 inner parts thereof at each side of the open-
ing between the wall parts so that it extends
beyond the edges of the inner parts and
15 stands to obscure said tangs and to direct-
ly oppose the pressure thereof.

In testimony whereof I affix my signature.
MAX MEYERSON.
